UNITED STATES PATENT OFFICE.

EVAN H. WADE AND JOHN L. NICHOLSON, OF CHICAGO, ILLINOIS, ASSIGNORS
TO AMERICAN LOCOMOTIVE EQUIPMENT COMPANY.

ART OF CONSUMING FUEL.

No. 851,830.

Specification of Letters Patent.

Patented April 23, 1907.

Application filed April 19, 1906. Serial No. 312,636.

To all whom it may concern:

Be it known that we, EVAN H. WADE and JOHN L. NICHOLSON, citizens of the United States, and residents of Chicago, Cook county, Illinois, have invented certain new and useful Improvements in the Art of Consuming Fuel, of which the following is a full, clear, and exact description, such as will enable others skilled in the art to which it appertains to employ the same.

Our invention relates to improvements in the art of burning or consuming fuel, and has special reference to improvements in the art or process as carried out in locomotive boiler furnaces and the like.

The object of our invention is to improve the combustion in furnaces, particularly in locomotive boiler furnaces.

The subject-matter of this application was first disclosed in, and is taken from, our pending applications, entitled "Locomotive Furnaces," filed Sept. 13, 1904, Serial Numbers 224,305 and 224,306, wherein the disclosure of the present invention is incidental to the description of and claims upon certain furnaces that are peculiarly suited to our novel process.

Our present invention is an improvement in the art of consuming fuel in furnaces; and consists in burning fuel in the lower part of a furnace, maintaining a partial supply of air through the bottom of said furnace, constricting the evolved gaseous body at a point above the burning fuel and below the furnace outlet and forming and maintaining within and completely across the constricted portion of said gaseous body, a stratum or barrier of hot air thereby augmenting the supply of air and compelling all of the combustibles to pass through said barrier and admix with sufficient air to insure proper combustion.

Our invention will be more readily understood by reference to the accompanying drawings, illustrating one form of locomotive boiler furnace which we are accustomed to use in carrying out our invention, which drawings form a part of this specification, and in which

Figure 1 is a vertical longitudinal section 50 of a locomotive boiler furnace constructed in the manner required by our novel process; Fig. 2 is a rear end elevation of the boiler; Fig. 3 is a horizontal section on the irregular section line $x-x$ of Fig. 1, viewed from beneath; and Fig. 4 is a compound transverse section, one-half thereof being on the line $y-y$ and the other half on the line $z-z$ of Fig. 1.

It is well known that many, and particularly locomotive, boiler furnaces are deficient 60 in grate area; in other words, suffer from lack of air, and that to secure the requisite evaporation in the boilers it is necessary to force their fires. In locomotives this is done by a steam blast, operating in the front end 65 of the boiler and causing a strong draft of air through the furnace grate. This method of promoting combustion is objectionable because the high velocity of the furnace gases too greatly reduces the time which should be 70 allowed for combustion and results in the carrying off of a considerable proportion of the combustible gases and products. An incidental disadvantage of the blast and the strong draft created thereby is that the latter tends to disrupt the bed of fuel on the grate and uncover the latter, necessitating great care in the firing of the furnace. The completeness to which combustion will progress in fuel depends upon the intimacy of 80 admixture between the combustible products and oxygen from the atmosphere, and upon whether or no sufficient oxygen is supplied to make proper combinations with all 85 of said products.

The object of our invention is to do away with the need for the strong draft through the furnace grate with all the disadvantages incident thereto, and to supply a sufficient quantity of oxygen to the burning fuel and 90 the gaseous products thereof in such manner as to insure substantially perfect combustion. This we accomplish by heating air and admitting it above the furnace grate, and by forming the heated air into a stratum or barrier which occupies the path of the gaseous and other products of the fuel at a point considerably back of or below the furnace out-

let. In this manner the vacuum and hence the updraft in the furnace is reduced, and, more important still, all of the combustibles are compelled to pass through a body of hot air wherefrom they are properly enriched with oxygen so that complete combustion must follow in the upper part of the furnace.

A thorough understanding of our novel improvement or process will be facilitated by a description of a furnace adapted thereto, such as is shown in the drawings.

The boiler, 2, represented in the drawings is of a common locomotive type, containing a furnace, 3, and the flues, 4.

15 5 represents the furnace grate, and 6, the furnace door.

Within the furnace are two arches, 7 and 8, composed of refractory material, such as fire bricks, and extending from side to side of 20 the furnace. The path of the gases between the grate and the furnace outlet or flues is constricted or limited to the capacity of the throat, 9, between the inlet ends of the arches. These arches contain a plurality of 25 air channels or ducts, 7¹—8¹, respectively, which communicate with the outer air through tubes, 7²—8², that extend through the rear and front water legs of the boiler. The inner ends of the arches contain cavities, 30 7³ and 8³, communicating with respective air ducts and opening through the undersides of the arches. These cavities extend from side to side of the furnace and are provided with inclined inner walls, 7⁴ and 8⁴, which constitute deflectors, so positioned that the currents of air entering through the arch ducts are formed into flat streams or sheets and are projected or directed toward the grate from opposite sides of the throat. Thus the currents of air from the arches are made to converge beneath the opening or throat, 9, between the arches, forming a complete barrier or stratum of air beneath said throat, the same extending across the throat and side to 45 side of the furnace.

The steps comprising and incident to our invention and the manner of using the invention will now be more fully described.

The exhaust nozzle (not shown) in the 50 front end of the locomotive boiler causes a draft of air upward through the grate as required to maintain initial combustion thereon. The partial vacuum in the furnace chamber caused by the exhaust of gases 55 through the boiler flues, results in the inflow of large volumes of air from the tubes 7²—8², and through the hollow or channeled arches wherewith they communicate. The bricks composing the arches are heated to a high 60 degree by the fire beneath; hence, the air

flowing through and discharged from the arches is perfectly prepared for admixture with the combustibles that rise from the bed of fuel. Although the air thus supplied above the grate is intensely hot, it is nevertheless cooler than the surface of the body of burning fuel, and also cooler than the ascending fuel gases and vapors. The air, therefore, naturally falls toward the grate and at least a portion of the admitted air spreads 65 over the fire to accelerate combustion at that point. Furthermore, the velocity of the air, due to the vacuum, is augmented by the expansion of the air in the arches, and as the swiftly moving currents of air come into contact with the oppositely inclined surfaces, 7⁴—8⁴, of the arches, the air is deflected thereby and projected downwardly. It is obvious that the two streams which emerge from the opposed arches converge at a point 80 beneath the furnace throat, 9, and together constitute a continuous stratum of air, which, as it extends from side to side of the furnace, effectually bars the passage of all combustibles except as they combine with the heated 85 air. The strong downward movement of the currents or sheets of air from the two arches is resisted by the up-draft through the furnace, the latter insuring their convergence beneath the throat. The air that is admitted around the lower part of the throat, as above explained, though already hot, quickly attains a still higher temperature in the atmosphere of hot furnace gases and for this reason more quickly enters into combination 90 therewith.

It is substantially true that where our process is employed only perfectly enriched or prepared combustibles are permitted to pass the throat of the furnace and that the 100 final combustion which occurs in the upper part or combustion chamber of the furnace is complete and perfect.

A distinct advantage of our invention is that the blast induced vacuum in the furnace 105 chamber is reduced by the admission of air above the grate, preventing both the disruption of the fire and the carrying over of cinders, less care being necessary in firing, and the top of the arch and the lower flues of the 110 boiler being no longer found loaded with cinders as in the past.

It is obvious that alterations in the physical conditions associated with the carrying out of our process, such as changes in the 115 form of the furnace throat, or in the manner of heating or introducing the air at the throat, may be made without departure from the process herein described.

Having thus described our invention, we 120

claim as new and desire to secure by Letters Patent:

The improvement in the art of consuming fuel in furnaces that consists in burning fuel in the lower part of a furnace, maintaining a partial supply of air through the bottom of said furnace, constricting the evolved gaseous body at a point between the burning fuel and the furnace outlet, and projecting into the constricted portion of said body and toward the burning fuel a plurality of converging streams of hot air, thereby establishing a barrier that is coextensive with the constricted portion of the gaseous body, substantially as described.

In testimony whereof, I have hereunto set my hand, this 22d day of March, 1906, in the presence of two subscribing witnesses.
